WHEEL BALANCING UNIT

Andrew J. Saulnier, 10820 Woodfair Road,
Fairfax Station, Va. 22039

Filed Apr. 28, 1972, Ser. No. 248,782

Term of patent 14 years

Int. Cl. D10—04

U.S. Cl. D10—82

FIG. 1

FIG. 2

FIG.3

FIG.4

FIG. 1 is a perspective view of a wheel balancing unit showing my new design;

FIG. 2 is a far side elevational view thereof;

FIG. 3 is a right side elevational view thereof;

FIG. 4 is a top plan view thereof.

The characteristic feature of my new design resides in the particular configuration of the weights and the supporting arms therefor.

I claim:

The ornamental design for a wheel balancing unit, as shown and described.
